UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING-MACHINES.

1,248,371.

Specification of Letters Patent. Patented Nov. 27, 1917.

Application filed December 14, 1915. Serial No. 66,782.

To all whom it may concern:

Be it known that I, JAMES R. MOFFATT, a citizen of the United States, residing at Chicago, in the county of Cook, State of Illinois, have invented certain new and useful Improvements in Looper Mechanisms for Sewing-Machines, of which the following is a description, reference being had to the accompanying drawing and to the figures of reference marked thereon.

The invention relates to new and useful improvements in looper mechanisms for sewing machines, and more particularly to the supporting mechanism for a thread carrying looper.

An object of the invention is to provide a supporting means for the looper carrier which is so constructed that the looper carrier may be removed from the supporting means on which it oscillates without disturbing or disconnecting said supporting means.

A further object of the invention is to provide a looper supporting means wherein the supporting stud for the looper carrier, together with the supporting bearings carried by the stud, may be detached from the looper rocker on which the stud is mounted.

A still further object of the invention is to provide a supporting means for a looper carrier wherein the cone bearings on which the looper carrier oscillates may be adjusted relative to each other without disturbing or changing the connection between the supporting stud on which the bearings are mounted and the looper rocker which carries said supporting stud.

These and other objects will in part be obvious and will in part be hereinafter more fully disclosed.

In the drawings, which show by way of illustration one embodiment of the invention:—

Figure 1 is a view in front elevation showing a portion of a sewing machine having the improved looper supporting mechanism applied thereto;

Fig. 2 is an enlarged front elevation of the looper carrier, a portion of the looper rocker, and the supporting means on which the looper carrier is mounted;

Fig. 3 is a plan view of the looper rocker, and the supporting stud on which the looper carrier is mounted;

Fig. 4 is a view in section through the looper rocker and the looper carrier showing the supporting stud and the bearings for the looper carrier; and

Fig. 5 is a perspective view with the parts separated, showing the looper rocker, the looper supporting stud, and the bearings for the looper carrier.

Prior to my invention, it has been customary to provide a looper rocker which is mounted in bearings so that said looper rocker may be oscillated, and on this looper rocker is mounted a looper carrier. The looper carrier is connected to the looper rocker by a pivotal supporting bearing so that the carrier may oscillate. The oscillation of the carrier causes the looper to enter and leave the needle loops while the oscillation of the looper rocker gives to the looper its needle avoiding movement. The present invention is directed to the manner of supporting the looper carrier on the looper rocker, and consists of a detachable supporting stud which is secured to the looper rocker by a threaded nut or the like, and this supporting stud carries the inner and outer bearings for the looper carrier. The outer bearing for the looper carrier is also adjustably and detachably connected to the supporting stud so that it may be removed for removing the looper carrier. This permits the bearings for the looper carrier to be relatively adjusted without disturbing the connection between the supporting stud and the looper rocker. It also permits the bearings, which are entirely independent of the looper rocker, to be made and tempered separately from the looper rocker.

Referring more in detail to the drawings, the invention is shown applied to a sewing machine having a supporting bed 1, in which is mounted to rotate a main shaft 2. Mounted in suitable bearings in the supporting bed is a looper rocker 3. Pivotaly attached to said looper rocker is a looper carrier 4 on which is mounted a threaded looper 5. Coöperating with said threaded looper is a needle 6 which is reciprocated in the usual manner. The looper carrier 4 is oscillated by a link 7, while the looper rocker 3 is oscillated from a suitable eccentric on the main shaft 2.

The looper rocker 3 is provided with

spaced bearing sleeves 8 and 9, and a lateral offset section in which is formed a circular recess 10 and an opening 11. The looper carrier 4 is mounted on a supporting stud 12. This supporting stud 12 carries cone bearings 13 and 14 on which the looper carrier is directly mounted. The cone bearing 13 is formed integral with the stud and is shaped to fit the recess 10. The base of the cone bearing is adapted to rest against the side face of the recess 10, and a nut 15 screwed onto the threaded end of the stud 12 firmly clamps the stud to the looper rocker. The outer cone bearing 14 is adjustably and detachably connected to the stud 12. Said cone bearing is connected to a sleeve which carries set-screws 16 and 17. One face of the stud is flattened at 18, and the removable cone bearing is so positioned that one of the set-screws will engage this flattened surface and thereby lock said cone against radial movement relative to the stud. The outer end 19 of the stud 12 is threaded and receives a lock nut 20.

From the above construction, it will be apparent that the outer cone bearing may be removed and the carrier replaced on the stud, after which this outer cone bearing may be secured to the stud in proper position to support the looper carrier. As the parts wear said outer bearing may be adjusted to take up the wear. This adjustment to take up the wear is accomplished without disturbing the set position of the stud on the looper rocker and without disturbing the bearing relation between the cones and the looper carrier. It often occurs that there are certain inaccuracies in the threads which hold the stud to the looper rocker, and when a threaded connection between the stud and the looper rocker is depended upon for adjustment to take up wear, the bearing surfaces of the cones are thrown out of alignment. By this improvement, however, where the stud when first connected to the looper rocker always retains its setting, there is no liability of throwing the parts out of alignment when adjustment is made for wear. It also often occurs in the tempering of parts that projecting parts are distorted. In other types, when the looper-supporting stud, together with its inner cone bearing, is formed integral with the looper rocker, the tempering of the parts often throws the same out of alignment. By the improved construction, however, when the inner cone is formed integral with the supporting stud, there is no liability of distorting the parts during tempering.

It is obvious that minor changes in the details of construction and the arrangement of parts may be made without depart-

ing from the spirit of the invention as set forth in the appended claims.

Having thus described my invention, what I claim as new and desire to secure by Letters Patent, is:

1. The combination of a looper rocker, a looper carrier, and means for supporting said looper carrier on said looper rocker, said means including a supporting stud detachably connected to said looper rocker, and devices whereby said looper carrier may be removed from the supporting stud without detaching said supporting stud from said looper rocker.

2. The combination of a looper rocker, a looper carrier, a supporting stud on which said looper carrier is mounted, said supporting stud having an inner cone bearing for said looper carrier formed integral therewith, devices for detachably connecting said stud to said looper rocker, and an outer cone bearing for said looper carrier adjustably connected to the outer end of said supporting stud.

3. The combination of a looper rocker, a looper carrier, a supporting stud on which said looper carrier is mounted, an inner cone bearing for said looper carrier attached to said supporting stud, said supporting stud having a threaded end projecting beyond said cone bearing, said looper rocker having a seat for the base of said cone bearing, and having an opening through which said threaded end of the stud extends, a locking nut for holding said stud on the rocker, and an adjustable outer cone bearing for said looper carrier secured to the outer end of said stud.

4. The combination of a looper rocker, a looper carrier, a supporting stud on which said looper carrier is mounted, an inner cone bearing for said looper carrier attached to said supporting stud, said supporting stud having a threaded end projecting beyond said cone bearing, said looper rocker having a seat for the base of said cone bearing, and having an opening through which said threaded end of the stud extends, a locking nut for holding said stud on the rocker, an adjustable outer cone bearing for said looper carrier mounted on the outer end of said stud, said stud having a threaded end projecting beyond the adjustable cone bearing, and a lock nut engaging the last-mentioned threaded end of the stud and engaging the outer face of said adjustable cone bearing.

In testimony whereof, I affix my signature, in the presence of two witnesses.

JAMES R. MOFFATT.
